UNITED STATES PATENT OFFICE.

ELMER R. POPE, OF HAMILTON, MASSACHUSETTS, ASSIGNOR TO UNITED SHOE MACHINERY CORPORATION, OF PATERSON, NEW JERSEY, A CORPORATION OF NEW JERSEY.

NAILING MACHINE.

Application filed August 5, 1925. Serial No. 48,373.

This invention relates to nailing machines and has for its object the improvement of the nailing dies and related elements of such machines, for example, as heel attaching machines, with a view to simplifying their construction and increasing their durability and the certainty and ease of their operation.

In my prior application Serial No. 702,412, filed March 27, 1924, I have disclosed a heel-nailing machine nailing die having improved self-adjusting means co-operating with the work into which nails are to be driven to determine the points at which the nails shall enter the work and to insure that the nails shall enter the work accurately at said points. In the mechanism illustrated in said application, laterally movable, self adjustable, upright, nail and driver guiding tubes are provided, in combination with a pattern plate which approximately determines the relative locations of their nozzle ends when the heel attaching nails are to be driven from them into the work. The pattern plate is moved out of engagement with the nozzle ends of the tubes when the nails are to be inserted in the tubes preparatory to the next attaching operation, and the tubes are then located and maintained in predetermined nail receiving positions by the resiliency of the nail drivers, which are at all times at least partially within the tubes. These drivers are sufficiently yielding to permit the tubes to be swung transversely until their nozzle ends are arranged in the desired nailing pattern when the said nozzle ends are again engaged by the pattern plate.

The present invention may, in a certain sense, be regarded as a development of, and improvement upon, the invention disclosed in the said application. As herein illustrated, a nailing die of the self adjusting type is provided in which the resiliency of the nail drivers is not depended upon to effect the positioning of the nail guides for loading purposes, and which, consequently, is not liable to be damaged or to be caused to fail to operate by breakage of drivers. Improved nail guide positioning means is provided, of such construction that definite accuracy in the nail receiving positions of the guides is insured and in the operation of which, moreover, no bending of the nail drivers is at any time necessary.

In the illustrated device each nail guide comprises a quill which, together with the corresponding driver, is mounted for universal lateral movement in a spherical bearing and the quills and drivers are always returned to upright, parallel positions, when the nail guides are ready to receive the nails, by the action of a spring pressed block upon the flat surfaces of hemispherical heads formed on the quills and fitting in the bearings already mentioned. The nail guides are shown as consisting of telescopic tubes or quills in which the drivers are secured and with which the drivers swing bodily without bending, when engaged by a pattern member having guide openings arranged in the pattern of the desired nailing.

For the purpose of centering the point of a nail as it is driven from the nail guiding tube, spring fingers are provided which are normally outside of the bore of the tube when the nail is to be inserted therein but are automatically moved into guiding engagement with the nail while it is being driven.

These and other novel features and advantages of the invention will best be understood and appreciated from reading the following detailed description of one successful practical embodiment thereof, in connection with the accompanying drawings, in which,

Fig. 1 is a view, partly in elevation and partly in section, of a set of nail drivers and guides, together with the mounting therefor;

Fig. 2 is a plan view of the device shown in Fig. 1;

Fig. 3 is a vertical section of one of the nail driving devices with a nail in position ready to be driven;

Fig. 4 is a view similar to Fig. 3 but showing the parts in the position which they occupy when the nail is driven; and

Fig. 5 is a view, partly in elevation, and partly in section, showing the relative positions of the parts when the driving stroke of the nail driver is about half completed.

In the drawings, a base plate 10 and a cover plate 12, taken together, constitute the driver block or plate of the nailing mechanism. The cover plate 12 is provided with recesses 14 for the reception of compression springs 16 which are confined by screws 18, threaded into the base plate 10. The springs 16 are at all

times under compression and tend yieldingly to hold the plates 10 and 12 together.

The plate 10 has formed in it a series of sockets having spherical bearing surfaces each of which constitutes a bearing for a complementary spherical bearing surface on the head 20 of a guide or quill member 22. A nail driver 24 is mounted in the member 22, in which it is securely maintained by a plug 26 screwed into a threaded extension 28 and bearing against the head end of the driver. The upper face of the head 20 is substantially flat and, when the driver is in an upright position, is flush with the top surface of the plate 10. The cover plate 12 is provided with perforations 30, somewhat larger than the quill members 22, through which said members pass, and the lower face of the cover plate bears directly upon the flat upper surfaces of the heads 20, maintaining the quills and drivers accurately in upright, parallel positions.

The quills and drivers, however, may be swung laterally in any direction, the yielding pressure of the cover plate 12 upon the flat surfaces of the heads 20, resulting from the force exerted by the springs 16, permitting the drivers and quills to be moved into such positions, for example, as that illustrated in Fig. 4.

Telescopically arranged inside of the quill member 22, and surrounding the driver 24, is another quill member comprising a nail guiding tube 32 arranged to slide longitudinally of the driver and normally projected to the position shown in Fig. 3 by a compression spring 34, which is capable of yielding to permit the tube 32 to telescope into the member 22 sufficiently to permit the nail 40 to be driven out of the quill. The length of the nail driver 24 is such that when the quill is telescoped the advance end of the driver projects from the quill, as shown in Fig. 4, whereby the nail is driven to the proper depth in the heel. A retaining sleeve 36 at the upper end of the member 22 prevents the guide tube 32 from escaping. Spring fingers 38 are secured in slots in the wall of the tube 32 and, when unconfined, occupy the positions shown in Fig. 3, permitting a nail to be freely inserted in the quill. When the quill is telescoped, however, as the driving stroke of the driver 24 occurs, the fingers 38 are pressed inward by the sleeve 36, their ends engaging the nail 40, as shown in Fig. 5, and centering the nail in the tube 32.

42 indicates a hollow die block within which the gang of nail driving devices is located, and 44 indicates a pattern plate for the desired nailing pattern to which pattern plate is secured a rubber heel locating and confining ring 46 of the usual type. The pattern plate is provided with a series of guide openings 48 arranged in approximately the nailing

pattern of the rubber heel 50 which is to be attached.

The guide openings 48, as shown in Figs. 3 and 4, are conical and, when the driver block 10, 12 is moved upward to drive the attaching nails, serve to guide the laterally movable nozzle ends of the self adjustable quills into approximately the desired nailing pattern, which is determined by the cavities 52 in the tread face of the rubber heel. The nozzle ends of the quills pass entirely through the guide openings 48, entering and engaging the walls of the cavities 52 in the heel and adjusting themselves to accurate register with the holes in the washers located at the bottoms of the cavities.

After the nails are driven the drivers and quills are retracted, whereupon the quills are returned always to the same predetermined, definite positions, ready to receive the next load of nails from nail loading mechanism which is common and well known in machines of this general type, as is also the mechanism for removing the pattern plate and rubber heel ring to permit the nail loader to be moved into position to deliver the nails to the quills.

Having described the invention, what is claimed as new and desired to be secured by Letters Patent is:

1. In a nailing machine, the combination of a plurality of self adjustable nail guiding tubes supported to permit transverse movement of their nozzle ends, a plurality of nail drivers operable through said tubes, and means, separate from the nail drivers, tending yieldingly to maintain the tubes in predetermined, definite positions.

2. In a nailing machine, the combination of a plurality of self adjustable nail guiding tubes supported to permit transverse movement of their nozzle ends, a plurality of nail drivers operable through said tubes, means, separate from the nail drivers, tending yieldingly to maintain the tubes in predetermined, definite positions, and a work engaging pattern member arranged to engage said nozzle ends to control the pattern of the nailing.

3. In a nailing machine, the combination of a series of self adjustable nail guides, a corresponding series of nail drivers operable through said guides, a pattern member having a series of guide openings arranged in approximately the nailing pattern of a heel, means, separate from the nail drivers, for maintaining the nail guides yieldingly in a pattern different from that of said guide openings, and means for advancing the nail guides into said guide openings to locate their nozzle ends approximately in said nailing pattern.

4. In a nailing machine, the combination of a laterally movable nail and driver guide, a nail driver operable through said guide, and yielding means, separate from the nail driver,

tending always to return said guide to a predetermined position.

5. In a nailing machine, the combination of a nail and driver guide supported to permit swinging movement, a nail driver operable through said guide, and means, separate from the nail driver, tending always to return said guide to an upright position.

6. In a nailing machine, the combination of a supporting member having a spherical bearing socket, a nail guiding quill having a spherical bearing surface to fit said socket and a flat surface, and quill positioning means bearing yieldingly upon said flat surface and tending to maintain the quill in a predetermined position.

7. In a nailing machine, the combination of a supporting member having a spherical bearing socket, a nail guiding quill having a spherical bearing surface to fit said socket and a flat surface, and a spring pressed, flat plate bearing upon said flat surface and tending to maintain the quill in a predetermined position.

25. 8. In a nailing machine, the combination of a nail guiding quill, a nail driver secured in said quill, and a mounting in which the entire

quill and driver are universally movable laterally.

9. In a nailing machine, the combination of a telescopic nail guiding quill, and a nail driver secured in said quill, said driver being of a length to project from the quill when the latter is telescoped.

10. In a nailing machine, the combination of a straight nail guiding quill, a permanently straight nail driver operable through the quill, and mounting means for the driver and the quill permitting their advance ends to be moved together laterally in all directions.

11. In a nailing machine, the combination of a telescopic nail guiding quill, a nail driver secured in one section of the quill and operable through the other section thereof, nail centering fingers normally outside of the bore of said other section to permit the insertion of a nail therein, said fingers being engaged by the first mentioned section and moved into guiding engagement with the nail when the driving stroke of the nail driver occurs.

In testimony whereof I have signed my name to this specification.

ELMER R. POPE.
